YORK, A CORPORATION OF NEW YORK

HOT-AIR HEATER

Application filed April 25, 1928. Serial No. 272,711.

This invention relates to so-called hot-blast heaters used mainly in heating and ventilating outfits for heating the air entering an apartment, the heating medium being steam or hot water. It relates to such heaters of the type having a series of parallel tubes containing the heating medium, the blast or current of air being circulated across and between the tubes in a direction transverse to the tubes; usually the tubes are vertical and are flattened, the heating medium entering at the top through a header, and the discharge being collected at the bottom by another header; between the headers the air current 10 passes usually in horizontal direction. The invention further relates to heaters of this character wherein the air is broken up by metal plates applied against or around the tubes and in heat-conducting contact with them, so that these plates are heated by the tubes and afford an extended surface for conducting heat to the air. Such plates have heretofore been made with angular or sinuous surfaces so as to slightly baffle the flow of air 20 and cause the air to impinge alternately against the upper and lower surfaces of contiguous plates, whereby to cause the air to more effectively take up heat from the plates.

The invention aims to improve the construction and increase the efficiency of heaters of the type described. Its novel features will be made manifest as the description proceeds.

The accompanying drawings show suitable embodiments of the invention applied both in heaters having a single row of flattened tubes and in those having a double row of tubes.

In the drawings,—

Figure 1 is a side elevation of a heater partly broken away so as to show the headers, tubes, and baffle plates, in vertical section, the plane of this section being on the line 1—1 in Fig. 2.

Fig. 2 is a horizontal section on the line 2—2 in Fig. 1.

Fig. 3 is an end elevation of the construction shown in Figs. 1 and 2.

Fig. 4 is a similar end elevation, but showing a part of the casing enclosing the heater and illustrating also a heater having only a

single row of steam tubes and showing also a different shape for the headers.

Fig. 5 is a detail on a larger scale of the lower part of Fig. 4, being partly in vertical section through the axis of one of the tubes.

Fig. 6 is a vertical section on the same scale as Fig. 5, and on the line 6—6 therein.

Fig. 7 is a perspective view of a nozzle or plug.

Fig. 8 is a plan thereof.

Fig. 9 is a plan of a fragment of one of the baffle plates, and

Fig. 10 is an edge view thereof.

Fig. 11 is a sectional elevation similar to Fig. 1, but showing also the supporting casing and illustrating the single tube construction shown in Fig. 4.

Fig. 12 is a fragmentary view, being a perspective or oblique projection of the upper part of the heater shown in Figs. 4 and 11.

Fig. 13 is a plan of the top header of Fig. 11.

Fig. 14 is an elevation of a modified form of header.

Referring to all of the drawings, *a* is an inlet pipe conducting steam or other heating medium into an upper header *A*; *B* *B* are the heating tubes which receive steam from the upper header *A* and which discharge the spent medium into a lower header *C* from which leads a drainage or outlet pipe *c*. The inlet and outlet pipes are shown in Figs. 1, 2 and 3 as horizontal pipes adjoining the ends of the respective headers; in Figs. 11 and 13 they are shown as vertical pipes, the one entering the top side of the upper header *A*, the other leading from the bottom side of the lower header *C*. The casing *D* is shown in Figs. 4 and 11 and consists simply of a four-sided frame formed of two upper members *d* *d* at the sides or ends, and two horizontal members *e* *e* at the top and bottom. The air flows through the rectangular space enclosed by these respective members, being caused to

flow through in a blast by the application of a blower or suction fan (not shown), or being induced to flow by any of the numerous means for circulating air, as, for example, by natural draft. The means for causing a blast of air

to traverse the heater are well understood and form no part of the present invention.

In heaters of this general character it is customary to flatten the tubes B B carrying the steam or other heating medium, their flat sides being in planes corresponding to the direction of flow of air through the heater. It is also customary to apply to or between these tubes, baffle plates E E in such manner as to force the air to flow in a slightly sinuous or zigzag path. The principal purpose of these baffle plates is to receive heat from the tubes and distribute the heat to the flowing air. In the constructions heretofore proposed the baffle plates have had only edge contact with the tubes, their union being effected by soldering or brazing whereby the heat-conductive joint is somewhat improved as compared with a mere edge contact of metal, although the heat conductivity thus attained is not in proportion to the increased area of the soldered surfaces because the alloys used for soldering or brazing have heat conductivity greatly inferior to that of copper or brass, which are the metals best utilized for the baffle plates. According to the present invention we greatly increase the heat conductivity at the junction between these plates and the tubes by forming the plates with upturned flanges which closely embrace the sides or external faces of the tubes over a considerable area. This construction is best shown in Figs. 5, 6 and 10, where the baffle plates E E are formed with upturned flanges b b which lie close against the outer faces of the tubes and are best made of such a close fit that they require to be forced into place in passing them over the tubes. In this manner such intimate and extended contact is secured as to afford a greatly improved heat conductivity without necessarily any resort to solder. It is preferable, however, to solder the parts by dipping in a solder bath, which leaves minute films of solder filling any slight interstices between the flanges and the tubes; and the poorer heat conductivity of the solder is compensated for by the greatly increased surface contact accomplished by the turning up of the flanges.

To insure the correct and equal spacing of the baffle plates the upturned flanges, or at least some of them, are made also to serve as spacing stops. Referring to Fig. 10, the flanges b' project a distance equal to the required spaces between the plates so that, as shown in Figs. 5 and 6, they insure the correct spacing of the plates by simply pressing each upper plate down until it rests upon these flanges. The flanges are located on opposite sides of the tubes (as shown in full and dotted lines in Figs. 5 and 10), so that their gauging effect applies on both sides. This, in connection with the perpendicular upturning of the flanges, insures that the plates shall lie parallel, as shown in Fig. 6. The plates

are punched out by dies which form an offset slit x, shown in Fig. 9, and the flanges are then turned up on both sides as far back as the dotted line y in Fig. 9, with the result of forming alternating shorter and longer flanges b b', as shown in Fig. 10.

The baffle plates, instead of being corrugated in curves, or in very sharp and abrupt steps as heretofore (which constructions have the disadvantage of obstructing the flow of air by breaking up the air current into numerous eddies which oppose the flow), are bent to form angularly-related surfaces, as clearly shown in the cross-sections, Figs. 5 and 10. The angles of these surfaces are such as to alternately deflect the currents of air flowing through between the plates so as to promote the most intimate contact between the air and the plates, but without the formation of eddy currents, which would obstruct such flow. The preferable angular relation is that shown, whereby the successive planes present an angle of 150 degrees to one another, or depart by 15 degrees from a medial horizontal plane. This angular relation has been carefully ascertained as that which attains the most efficient heat convection with the least obstruction to the flow of air.

The baffle plates are shown as having five such angular portions of equal width, plus a similar angular portion at the opposite ends or margins of the plate, which latter portion is somewhat narrower, preferably from one-third to one-half of the width of the other plane portions. While the number of such angular planes may be varied, and would depend upon the width of the flattened tubes B B, yet for the general proportionate dimensions shown, this relation of the angular planes is found to give the best results.

The headers A, C, are constructed of sheet metal (preferably brass or copper) and are best made as duplicates; they are formed each of an upper and lower section having meeting flanges f united by brazing. For vertical inlet and outlet pipes it is preferable to use the construction shown in Figs. 4, 11, 12 and 13, where the upper and lower sections g, h, are of equal width, so that the abutting flanges f form a medial joint, as clearly shown in Figs. 11 and 12. The sections g, h, are thus made exactly alike, except that one of them is perforated to receive the tubes B B. They have flat upper and lower faces which are perforated where the respective tube or pipe connections are made. The inlet a is screwed into a nipple i (Fig. 11) having a flange j which is soldered within the header; similarly, the outlet pipe c is screwed into a nipple z having a flange j' which is soldered into the lower section g of the header C. The sections h h of the two headers have their flat sides perforated to receive the ends of the tubes B B; the ends of the tubes pass through the holes thus punched in

the flattened portion and the joint is united by brazing, as shown at *k* in Figs. 5 and 6. The construction just described is suitable for heaters having a single row of tubes *B*; for those having a double row of tubes the construction shown in Figs. 1, 2 and 3 is preferable. In this construction the headers *A* and *C* are made of sections *g'*, *h'*, of unequal width, so that their flanges *f* form a joint which is in a plane somewhat closely approaching the plane of the flat side of the section *h'*, this flat side being of increased width in order to be punched with holes for receiving the two rows of tubes *B B*. These tubes *B B* are preferably in staggered relation, as clearly shown in Fig. 2. This construction best lends itself to the application of inlet and outlet pipes *a*, *c*, at the ends of the headers. For this purpose the header ends 20 are made as separate pieces or heads *m*, *n*, respectively; the heads *m* are of cast metal sufficiently massive to form threaded openings for receiving the respective pipes; the heads *n* at the opposite ends of the headers 25 may be made of thin metal, as their function is solely to close the ends of the headers; in the case of both heads, the sheet metal of the header sections is brazed to flanges or portions of the heads which enter within the 30 ends of the sheet metal sections.

In order to effect a uniform distribution of steam (or other heating fluid) from the header *A* into the tubes *B B*, inlet nozzles in the form of plugs are provided, lettered *G G*; one of these is shown separately in Figs. 7 and 8. These nozzle plugs are formed with a convex portion *p* having an outer flange *q* and diminishing therefrom to a reduced bottom portion in which is punched a contracted 40 opening *r*. The plug portion *p* is of such shape and size as to fit tightly within the end of the tube *B*; the flange *q* overlies the end of the tube, thereby limiting the entrance of the plug into the tube; and the contracted 45 openings *r r* serve to distribute the heating medium and prevent its flowing more readily into the tubes *B B* nearest the inlet, thereby attaining an approximately equal flow of heating medium through all the tubes of the 50 series. It is preferable to omit the nozzle plugs *G G* from the last tube or tubes *B*.

The nozzle plugs *G G* may also be used with some advantage at the lower ends of the tubes *B B*; and they are so shown in 55 Figs. 5 and 6, as well as in Figs. 1 and 11; but in this location their restricted nozzle openings *r r* have no necessary function, since there is no need of regulating or obstructing 60 the outflow of condensation in the case of steam; nevertheless, thus used, they have the advantage of strengthening the joint between the tubes and the header; in either location the flanges *q* assist in forming a capillary 65 chamber which is filled by the solder *k* form-

ing the tight joint between the tubes and header.

In a structure of this character it is important to provide against the possibility of injury by freezing. Such heaters are commonly used in factories, lofts, and the like, which are closed down overnight or over week-ends, and there is always some risk that steam used as the heating medium may condense and the condensation may fill either or both of the headers, and by freezing therein might rupture the headers and occasion leaks. To guard against this danger the headers are so constructed as to make them expansible to the extent necessary to tolerate the expansion incident to the conversion of water into ice. This is provided for in part by the formation of the headers with one or both sides flattened, so that such flattened side may bulge slightly if ice forms within the header. It is also in part provided for by the formation of the header with corrugations *t t*, best shown in Figs. 12 and 13, which corrugations afford a surplus of metal further contributing to expansibility of the header.

Figure 14 shows a header (being either the top or bottom header) for two rows of tubes similar in construction to that shown in Figs. 4, 11, 12 and 13, except that the sections *g h* are made wider to accommodate the two rows 95 of tubes. The corrugations *t t* are provided as in the single tube construction.

For the mechanical support of the heater in the casing *D* any suitable construction may be provided; and to the casing may be added any ornamental outer portion which may be desired. In Figs. 4 and 11 two supporting connections are shown; in Fig. 4 the headers are connected by bracket pieces *s s* to the upper and lower plates *e e* of the frame; in Fig. 11 the frame *D* has plates or strips *u*, *u'*, which receive between them the projecting flanged joints *f* of the respective headers, and thereby strongly support the latter. These strips *u*, *u'*, also serve as strengthening members of the frame *D*, so that the end portions *d d* may be formed by filling plates of thin sheet metal.

The various details of construction shown and described as being part of the preferred embodiment of the invention may be varied or departed from according to the precise location and proportions of the heater, such variations being within the skill of heating engineers or designers.

Obviously, the construction herein shown and described may be used for cooling instead of heating; thus it is applicable for cooling air by using a refrigerated circulating medium within the tubes.

We claim as our invention:—

1. In a heater of the type comprising hot tubes and a succession of flat baffle plates, the latter formed with successive angular portions in planes substantially 150 degrees

- to one another, and substantially 15 degrees to the general medial plane of the plates, and the plates uniformly spaced with their plane portions parallel to form zigzag passages to repeatedly deflect the air without forming eddies.
2. In a heater of the type comprising hot tubes and baffle plates, the tubes flattened and the baffle plates applied in regular succession upon the tubes and bent into successive angular planes adapted to be traversed in succession by air flowing between the tubes and parallel with their flattened faces, whereby to repeatedly deflect the air as it flows past or between the respective tubes, but without breaking up the flow of air into eddies.
3. A heater of the described type having a sheet metal header with holes receiving the ends of the tubes and flanged plugs entering the ends of the tubes for strengthening the joint between the tubes and header, said plugs having flanges underlying such joints to form an annular capillary channel for holding solder.
4. A heater of the described type having a sheet metal header with elongated holes receiving the flattened ends of the tubes and sheet metal plugs fitting within the tube ends for strengthening the soldered joints.
5. A heater of the described type, having an enclosing casing, the heater having a header with external flanges, and the casing having opposite members embracing such flanges between them to support the heater within the casing.
6. In a heater of the type comprising flattened hot tubes and baffle plates, the baffle plates slitted and struck up to form flanges closely embracing the flat sides of the tubes, these flanges being intermittent and of unequal depth, the deeper flanges serving to correctly space the plates and being alternated on opposite sides of the tubes.
7. In a heater of the type comprising flattened hot tubes and baffle plates, the latter formed with bent flanges closely embracing the flat sides of the tubes, the baffle plates angularly bent at intervals and their flange formed between such bends, the flanges of a depth to insure the correct spacing of the plates and alternated on opposite sides of the flattened tubes.
8. A heater of the described type having sheet metal headers and hot tubes extending between them with individual contracted nozzles entering the tubes, their wider portions substantially filling the ends of the tubes and serving to strengthen the joints between the tubes and the header.
- 60 In witness whereof, we have hereunto signed our names.
